(57) **CLAIM**

The ornamental design for a tray for housing remote transmitters, as shown and described.

DESCRIPTION

FIG. 1 is a top plan view of a tray for housing remote transmitters showing my new design.

FIG. 2 is a bottom view thereof.

FIG. 3 is a front plan view, the rear plan view being identical thereof.

FIG. 4 is a right side plan view, the left side plan view being identical thereof; and,

FIG. 5 is a upper right perspective view thereof.

The portions shown in dashed lines form no part of the claimed design.
